Primary Examiner — Mark A Goodwin(74) *Attorney, Agent, or Firm* — Tucker Ellis LLP;
 Michael G. Craig; Heather M. Barnes(57) **CLAIM**

The ornamental design for a loader carrier for implements, as shown and described herein.

DESCRIPTION

FIG. 1 is a front-top perspective view of a new design for a loader carrier for implements in one implementation;
 FIG. 2 is a left side view of the new design for the loader carrier for implements, in one implementation;
 FIG. 3 is a front-top perspective view of the new design for the loader carrier for implements;
 FIG. 4 is a rear-bottom perspective view of the new design for the loader carrier for implements;
 FIG. 5 is a front view of the new design for the loader carrier for implements;
 FIG. 6 is a rear view of the new design for the loader carrier for implements;
 FIG. 7 is a top view of the new design for the loader carrier for implements;
 FIG. 8 is a bottom view of the new design for the loader carrier for implements;
 FIG. 9 is a left side view of the new design for the loader carrier for implements; and,
 FIG. 10 is a right side view of the new design for the loader carrier for implements.
 The broken line representations in the figures show unclaimed environment or boundaries, and thus form no part of the claimed design.

1 Claim, 8 Drawing Sheets# US D1,026,968 S
